BILLFOLDS

Jac B. Anderson, West Bend, Wis., assignor to Enger-Kress Company, West Bend, Wis., a corporation of Wisconsin

Application June 24, 1952, Serial No. 295,189

1 Claim. (Cl. 150—38)

This invention relates to improvements in billfolds.

At the present time there is a demand for billfolds which are capable of holding a relatively large number of cards, photos or the like, as well as bills, and it is important that billfolds of this type be readily foldable with both the cards and bills therein, and that the resulting article be relatively slim and trim, notwithstanding the contents.

It is a general object of the present invention to provide a billfold having an expandible card holding pocket superimposed on one of the inner panels thereof, the pocket being so arranged and attached as to always present a neat appearance, regardless of the number of cards therein, and the pocket being expandible at its outer end as well as at the sides.

A more specific object of the invention is to provide a billfold having panels forming conventional card receiving pockets at both ends thereof, there being a second pocket having gusseted sides and end superimposed on one of said panels.

A further object is to provide, in a billfold, a gusseted card pocket construction wherein there is no interference with the folding action of the billfold, and wherein the gussets which provide for expansion of the card pocket tend to normally lie flat when the pocket is not filled with cards, and wherein the edges of the expandible pocket remain within the confines of the billfold and do not tend to project over the edges in an unsightly manner.

A more specific object is to provide, in one form of the invention, a gusseted card pocket construction wherein the gusset forming sections are integral with the outer face of the expandible pocket and are formed with tongues which are cooperable with slot in a portion of the billfold to connect the pocket to the fold in such a manner that it normally tends to lie flat, while nevertheless providing for expansion when needed.

A further object of the invention is to provide a billfold construction as above-described, including a gusseted card pocket, wherein the end-gusset forming section is so arranged with respect to the end of the fold that it is always in place, and so that there is no portion tending to project beyond the end of the fold when there are no cards in the pocket.

Other objects of the invention are to provide an improved billfold which is neat and attractive in appearance, which is relatively simple to manufacture, and which is otherwise well adapted for the purpose described.

With the above and other objects in view, the invention consists of the improved billfold, and all its parts and combinations, as set forth in the claim, and all equivalents thereof.

In the accompanying drawings, illustrating two complete embodiments of the invention, in which the same reference numerals designate the same parts in all of the views:

Fig. 1 is a plan view of one form of billfold in flat unfolded condition;

2

Fig. 2 is a longitudinal sectional view on an enlarged scale through the portion of the fold having the expandible card pocket, taken approximately on the line 3—3 of Fig. 1;

5 Fig. 3 is a view on the same scale as Fig. 2 taken on the line 2—2 of Fig. 1;

Fig. 4 is a fragmentary sectional view showing a portion of Fig. 2 with only the important cooperating parts illustrated.

10 Fig. 5 is a fragmentary sectional view showing a portion of Fig. 3 with only the important cooperating parts illustrated, the dot and dash lines indicating a partially collapsed condition;

15 Fig. 6 is a plan view of the outer side of a cut and scored blank for forming the main body of the billfold of Fig. 1;

Fig. 7 is a plan view of the outer side of a cut and scored blank for forming the expandible card pocket;

20 Fig. 8 is a fragmentary plan view showing the reverse or inner side of the slit flap of Fig. 6 as it appears after the blank of Fig. 7 has been connected thereto, part of the material of the fold proper being broken away at a corner;

25 Fig. 9 is a plan view of a modified form of billfold in unfolded condition;

Fig. 10 is a longitudinal sectional view through the portion of the fold having the expandible pocket, taken along the lines 10—10 of Fig. 9;

30 Fig. 11 is a sectional view on the same scale as Fig. 10, taken along the line 11—11 of Fig. 9;

Fig. 12 is a fragmentary sectional view showing a portion of Fig. 11 on a larger scale; and

Fig. 13 is a fragmentary sectional view showing a portion of Fig. 10 on a larger scale.

35 Referring more particularly to the form of billfold shown in Figs. 1 to 8 inclusive, the billfold includes a back or outer wall 15 having panels 16 and 17 foldably connected thereto on a line of scoring 18; having a flap 19 foldably connected on a line of scoring 20, with small tongues 21 adjacent the ends of the flap 19; and having end flaps 22 and 23 foldably connected to the wall 15 on lines of scoring 24 and 25 respectively. The panel 16 is provided with slits 26, 27, 28, 29 and 30, and the panel 17 is provided with a slit 17.

40 The blank for forming the expandible card pocket (see Fig. 7) includes a main panel 31 having a gusset forming extension 32 foldably connected to one edge on a line of scoring 33 and having a gusset forming extension 34 foldably connected to another edge on a line of scoring 35.

45 Projecting from the gusset forming extension 32 are tongues 36 and 37, and projecting from the gusset forming extension 34 are tongues 38 and 39. There are also notches 40 and 41 at the inner ends of the gusset forming extensions.

50 At the end of the blank of Fig. 7 is an end gusset forming extension 42 having a tongue 43 projecting therefrom.

55 In assembly, the card pocket forming blank of Fig. 7 is placed over the panel 16 of Fig. 6. Next, the gusset forming portions 32 and 34 are folded on the lines 33 and 35, and the end gusset forming extension 42 is folded on the line 44. The tongues 36, 37, 38 and 39 are inserted through the slits 27, 26, 29 and 30 respectively, and the tongue 43 is inserted through the slit 28. These tongues are then glued in position on the inner side of the panel 16 in the manner shown in Fig. 8, the gusset forming extensions 32 and 34 at the sides projecting inwardly from the fold lines 33 and 35, as shown in Figs. 3 and 5 and in collapsed condition being substantially parallel with the panel 16 so that the superimposed card pocket lies very flat on top of the panel in spite of the gusset sections when there are no cards in the pocket.

The end gusset forming extension 42 also projects inwardly from the fold line 44 in a plane substantially parallel with the panel 16 when the pocket is collapsed. This portion is shown in somewhat expanded condition in Figs. 2 and 4. It is preferred to stitch the tongue 43 as at 43' as well as glue it.

As shown by the broken out corner of Fig. 8, the ends of the gusset forming section 42 overlap the ends 32' of the side gusset forming sections 32.

After the card holding pocket has been thus assembled on the panel 16, the end flap 23 is folded over and its tongue 45 is inserted in the same slit 28 that receives the end tongue 43 of the card forming pocket, as shown in Fig. 4. This latter tongue is also glued in place.

The remainder of the billfold is assembled in a more or less conventional manner. That is, the top edges of the panels 16 and 17 are folded over the edge 46 of an intermediate piece 47 and secured thereto, and the end flap 22 is folded over so that its tongue may be inserted into and glued in place in the slit 17', as shown in Fig. 1.

The card holding pocket formed by the panel 31 is adapted to be closed by a flap 48, the latter having its inner edge suitably secured to the panel 16 as at 49 in Fig. 2, and being provided with an elongated tongue 50 which is insertible through a loop 51, the latter having its ends secured in the slits 52 of Fig. 7, in a well known manner.

In Figs. 9-13 a modified form of the invention is illustrated. This billfold also includes a card holding pocket having expandable sides and end just as in the form of the invention of Figs. 1 to 8.

Referring to the billfold illustrated in Figs. 9-13 and designated generally by the numeral 53, this billfold is more or less conventional for the most part and includes an outer or back wall 54. A panel 55 is folded from the lower edge of the wall 54, as shown in Fig. 9 to form a pocket, and a panel 56 (see Fig. 10) which is also folded from the lower edge of the billfold forms an inner card holding pocket between it and an intermediate layer of material 57 as is well known in the art.

The expandable card holding pocket which forms the subject matter of the present invention includes a panel 58 having gusset forming extensions 59 (see Figs. 11 and 12) which are stitched to the panel 56 as at 60. The extensions 59 have longitudinal fold lines 59'. The card holding pocket also includes a gusset forming end extension 61 which is disposed as shown in Figs. 10 and 13, there being an end flap 62 which is folded from the back wall 54 of the billfold over the free edge of the extension 61, with all of the layers stitched together as shown at 63 in Fig. 13. The extension 61 has a longitudinal fold line 61'. Thus, the end gusset forming extension is sewed in simultaneously with the turned over end flap 62 of the back or outer wall 54.

It is apparent from the above that both forms of the improved billfold have an expandible card holding pocket which always maintains a neat and trim appearance regardless of the number of cards therein.

In both forms of the invention the pocket forming member is formed separately from the billfold proper and has gusset forming extensions which provide for expansion on two sides as well as on an end edge.

In addition to the above, in both forms of the invention there is a flap folded from the end edge of the outer

wall of the billfold over the adjacent end of the panel, which flap is so secured to the panel and to the end gusset forming member as to permit expansible movement of the end of the pocket forming member, while keeping the parts neatly connected and while effecting a neat closing of the end of the billfold proper.

Although only two forms of the invention have been shown and described, various other changes and modifications may be made without departing from the spirit of the invention, and all of such changes are contemplated, as may come within the scope of the claim.

What I claim is:

In a billfold having an outer wall and having a panel folded from a longitudinal edge of said outer wall to a superimposed position on the inner side of said outer wall and having slits spaced inwardly from its side and end edges, a pocket forming member superimposed on said panel having gusset forming extensions folded from its side edges beneath the latter, said member also having a gusset forming extension folded from the edge of its outer end beneath said end, said last mentioned extension being adjacent an end edge of the outer wall of the billfold, tongues projecting from said side gusset forming extensions with each tongue received in one of the slits of the panel, a tongue projecting from said end gusset forming extension and received in a slit of the panel and having its ends in overlapping relationship with adjacent ends of tongues of said side gusset-forming extensions, means for securing said tongues to the under-surface of said panel, the location of the slits in the panel inwardly of the edges of the pocket forming member providing for expansible movement of the pocket forming member at its sides as well as at its outer end, and a flap folded from said end edge of the outer wall over the adjacent end of said panel and having a portion projecting through the same slit of the panel which receives the tongue of the end gusset forming extension, a closure flap for said pocket secured at one edge to said panel adjacent the inner end of said pocket forming member along a line which extends transversely of the billfold and having an elongated tongue projecting from its opposite edge, and an external loop on said pocket forming member extending transversely thereof positioned to slidably receive said tongue in any position of expanded movement of the pocket forming member, means located inwardly of the edge of the end of said pocket forming member for securing said flap portion in said position beneath said tongue of the end gusset forming extension.
